UNITED STATES PATENT OFFICE.

EDWARD F. POLAND, OF BOSTON, MASSACHUSETTS.

WASHING-MACHINE.

1,344,089.

Specification of Letters Patent. Patented June 22, 1920.

Application filed January 26, 1917. Serial No. 144,718.

To all whom it may concern:

Be it known that I, EDWARD F. POLAND, a citizen of the United States, residing at Boston, in the county of Suffolk and State 5 of Massachusetts, have invented an Improvement in Washing-Machines, of which the following is a specification.

Certain types of washing machines, as usually constructed, have comprised a pair 10 of side plates or frames, and a shell having a flange at each edge adapted for engagement with the side plates, which flanges are riveted to the side plates, thereby to rigidly connect the shell therewith, thus to complete 15 the frame structure and provide a water-containing receptacle; and a suitable packing, such for instance as sheet lead, is interposed between the flanged edge of the shell and the side frames, which is tamped to produce a water-tight joint. With such a structure, it is a serious fault to utilize the shell 20 as a component part of the frame.

In case a joint leaks, it must be repaired from the inside of the receptacle, which 25 operation is attended with considerable difficulty. In case the shell wears out, or is so injured that a new shell is required, the old one must be detached from the side plates to admit of a new one being substituted, and 30 when detaching the same, the entire, or substantially the entire frame structure must be disassembled. In case of a fire, the lead packing usually melts, and the tight joint is destroyed. Hence, repairs of an extensive 35 nature can only be made satisfactorily at the factory, which necessitates shipping the machine to the factory with the attendant delays in transit as well as the additional expense.

40 I have discovered that by providing the side-plates with means for rigidly supporting them in their respective relative positions independently of the shell, that the shell may be connected with the side-plates 45 by a very simple form of joint, which, in case of leakage, may be repaired from the outside of the shell, or in case a new shell is required, said new shell may be secured in place at the laundry, without the necessity 50 of shipping the machine to the factory.

Furthermore, a type of joint may be employed wherein the ends of the shell may be devoid of flanges, and rivets are not required to connect said ends with the side-plates. 55 Such joint may consist of a groove formed in the inner side of each side plate, which

grooves are adapted to receive the ends of the shell and said grooves are made much wider than the thickness of the wall of the shell to provide spaces in the grooves at one 60 side of the wall of the shell to receive a mass of molten lead or equivalent packing material which may be run into the grooves after the shell has been placed therein. The wall of the shell may be arranged contiguous 65 the inner wall or side of the grooves, and in such case, the mass of molten lead will be arranged on the outside of the wall of the shell. This type of joint for this purpose has many advantages but by means inde- 70 pendent of the shell, such joint cannot be employed for the reason that it is not strong enough to connect the shell with the side plates and hold said parts assembled, so that they form component parts of the frame 75 structure.

Figure 1 is a front elevation of a washing machine embodying this invention.

Fig. 2 is an end view of the same.

Fig. 3 is a rear elevation of the same. 80

Fig. 4 is an inner side view of one of the side plates of the frame structure which also serves as an end wall for the water-containing receptacle.

Fig. 5 is a fragmentary sectional detail 85 view of a joint which may be employed.

Fig. 6 is a similar detail view of a modified form of joint.

The frame-structure of the machine, as here shown, consists of a pair of side-plates 90 10, 12, of circular formation, having supporting legs 13; a substantial bar or beam 14 arranged horizontally to rigidly connect said side-plates together at the rear of the machine, said bar or beam being arranged 95 with its ends abutting against adjacent faces of elongated ears 15 on the side-plates and secured thereto by screws 16 extended through said ears and into the ends of the beam; and several long stay bolts 17 which 100 are rigidly connected to the two side-plates, there being four such bolts here shown, two of which are arranged within the margins of the side-plates, and two are arranged outside of the margins of the side-plates, being at 105 the tops of the supporting legs. However, any other suitable form of bar, beam, or stay bolts, or equivalent members may be employed, the idea being to provide ample connecting-means for rigidly connecting together the side-plates, so as to form a rigid 110 frame structure, independent of the shell

which is connected with the side-plates, and which forms in connection therewith, a water-containing receptacle.

20 represents such a shell, which is of 5 semi-circular formation in cross-section, and adapted for engagement with the lower half or portion of the side-plates, so that together with said side-plates, a water-containing receptacle is produced.

10 Each side-plate has a deep groove 21 formed on its inner side or face at or near its margin adapted to receive one end of the shell. This groove may be formed by providing a pair of parallel flanges 22, 23, on 15 the inner side or face of the side-plate, as represented in Figs. 4 to 6. The ends of the shell are placed in these grooves, being arranged therein contiguous the inner wall of the grooves, see Fig. 5, and the grooves are

20 made of sufficient width to provide spaces outside of the wall of the shell adapted to receive a metallic packing, such, for instance, as molten lead or spelter. In Fig. 5, a groove is represented as having substantially parallel sides and the end portion of 25 the wall of the shell may be more or less roughened thereby to more securely enable the metallic packing to hold the shell in place. In Fig. 6, a dove-tailed groove is 30 formed which obviously more securely holds the metallic packing in place. The metallic packing inherently unites with the metallic side-plates and shell, so that a water-tight joint is produced.

35 With this structure, it will be seen that in case the joint leaks, it may be easily repaired at the outside of the shell, or in case the shell needs repairs, or a new shell is required, the old shell may be removed, and a 40 new shell supplied, without the necessity of disassembling the entire structure or sending the machine to the factory, or in case of a fire, and the metallic packing melts, new metallic packing may be easily supplied without 45 disassembling the machine.

The side-plates of the machine each have an elongated radial slot 30 extended to its center or thereabout to enable the usual shaft to be placed in position, and suitable 50 covers 31 are provided for these slots.

Furthermore, suitable means are provided for closing the top of the water-containing receptacle which may comprise a circularly-formed plate 35, rigidly connected to the 55 margins of the side-plates, and a circularly-formed cover 36 hinged thereto.

I claim:—

1. In a washing machine, the combination of a shell, a pair of spaced-apart side-plates 60 having grooves in their adjacent sides, a plurality of supporting members extended between said plates rigidly connecting them together at their margins to form a rigid frame structure and to maintain said side-

plates in spaced-apart relation independently of said shell, said shell having its ends received in the grooves in said side-plates, and metallic packing arranged in the grooves with the ends of the shell on the outside of the receptacle, said shell and side- 70 plates forming a water-containing receptacle. 65

2. In a washing machine, the combination of a shell, a pair of spaced-apart side-plates having grooves in their adjacent sides, a plurality of supporting members extended between said plates rigidly connecting them together at their margins to form a rigid frame structure and to maintain said side- 75 plates in spaced-apart relation independently of said shell, said shell having its ends received in the grooves in said side-plates, contiguous the inner walls thereof, and metallic packing arranged in the grooves at the outside of the shell, said shell and side-plates 80 forming a water-containing receptacle. 85

3. In a washing machine, the combination of a shell, a pair of spaced-apart side-plates having grooves in their adjacent sides, elongated ears in said plates, a bar extending 90 horizontally and connected to said ears, a plurality of long bolts connected to the margins of said side-plates, thus to form a rigid frame structure and to maintain said side- 95 plates in spaced-apart relation independently of said shell, said shell having its ends received in the grooves in said side-plates, and a mass of metallic packing compacted in the grooves with the ends of the shell on the outside of the receptacle, said shell and 100 side-plates forming a water-containing receptacle. 105

4. In a washing machine, the combination of a pair of spaced-apart end-plates, means rigidly connecting and separating them, a curved shell disposed between said end- 110 plates, and means whereby said end-plates and shell are connected to form a water-tight joint comprising, said end-plates having deep grooves in their adjacent faces in which the ends of said shell are received with its inner face contiguous the inner edges of the grooves, said grooves being materially wider than the thickness of the shell, and a metallic packing compacted into 115 the spaces between the shell and the groove on the outside of the shell whereby to force the inner face of said shell into firm contact with the inner edges of the grooves and externally seal the vessel. 120

In testimony whereof I have signed my name to this specification in the presence of two subscribing witnesses.

EDWARD F. POLAND.
